UNITED STATES PATENT OFFICE.

HOWE E. DANTZEBECHER, OF GERMANTOWN, PENNSYLVANIA.

METALLIC CALKING FOR BOATS.

SPECIFICATION forming part of Letters Patent No. 783,684, dated February 28, 1905.

Application filed August 11, 1903. Renewed August 29, 1904. Serial No. 222,606.

To all whom it may concern:

Be it known that I, HOWE E. DANTZEBECHER, a citizen of the United States, residing at Germantown, in the county of Philadelphia and 5 State of Pennsylvania, have invented certain new and useful Improvements in Metallic Calking for Boats, of which the following is a specification.

My invention has relation to a metallic calking for the seams of boats; and in such connection it relates to the construction and arrangement of such a calking.

Heretofore in stopping the seams of boats the usual calking was of cotton or oakum 10 tamped into the seams by expert workmen. Such calking not only requires much labor and time to insert in the seams, but after being tamped therein is liable to be displaced by the movement of the planks when the parts 15 calked warp under heat and cold or shrink and swell when the boat is placed in and out of the water. Some attempts to replace the cotton or oakum-calking by metallic strips have been made with more or less success. 20 Where such strips were used for calking the bottom of the boat, parts of the strip were in contact with the water in the interior or on the exterior of the boat-bottom and quickly 25 corroded and disintegrated. Again when so used the strips were unable to adapt themselves to the warping, shrinking, and swelling of the planks, and hence were easily displaced from the seams even when the strip was bolted or riveted to the planks.

30 The object of my present invention is to provide a calking-strip of metal readily adapted to be inserted between adjacent planks of the boat and when so inserted to be entirely surrounded by said planks, said strip being 35 so formed as to yield with the planks when said planks are distorted without opening the seam between the planks.

The nature and scope of my present invention will be more fully understood from 40 the following description, taken in connection with the accompanying drawings, forming part hereof, in which—

Figure 1 is a transverse section of a boat having the metallic calking-strips embodying 45 main features of my invention inserted in its

seams. Fig. 2 is an enlarged transverse sectional view of several adjacent planks of the boat with the calking-strips stopping the seams between said planks, and Fig. 3 is an enlarged perspective view of the metallic calking-strip. 55

Referring to the drawings, *a a* represent the frames of a boat to the base of which the planks *b*, forming the bottom of the boat, are secured. The contiguous sides of adjacent planks *b* are vertically cut out, as at *b'*, and then horizontally cut into, as at *b''*, to form a substantially L-shape slot intermediate of the inner and outer faces of each plank *b*. When two planks *b* are arranged side by side, as 60 illustrated in Figs. 1 and 2, the L-shape slots of contiguous sides form a substantially T-shape slot extending longitudinally in the bottom of the boat. The calking-strip *d* comprises a strip of springy or resilient metal 65 bent intermediate of its ends, as at *d'*, to form two wings *d'' d''*, diverging slightly from the point *d'*, and each wing *d''* terminates in a flange *d''*, the flanges *d''* extending in opposite directions to form a strip which in cross-section 70 is substantially V shape. In calking the boat the wings *d''* of the strip are inserted in the side grooves *b'* and the flanges *d''* are inserted in the horizontal grooves *b''*, and when so inserted the strip effectually calks the seam *b'* 75 between adjacent planks *b*, and is completely surrounded by the planking *b* as clearly illustrated in Fig. 2. Should the bottom of the boat contract or shrink and the seams tend to open at the base of the planks, then the wings 80 *d''* of the strip bend outward away from each other upon the point *d'*, as indicated at the right-hand seam in Fig. 2, and will still effectually calk the seam. Should the bottom of the boat 85 expand in an opposite direction, the only effect of the movement of adjacent planks *b* will be to clamp the wings *d''* more tightly together, as illustrated at the left-hand seam in Fig. 2, and the calking or stoppage of the seam will not be impaired. 90

Having thus described the nature and object of my invention, what I claim as new, and desire to secure by Letters Patent, is—

A means for calking seams of boats, comprising a metallic strip of substantially V 95

100

shape in cross-section inserted into a comple-
mentally - formed slot extending longitudi-
nally in contiguous faces of the planks at the
seam to be calked and said strip being com-
5 pletely inclosed by said planks, substantially
as and for the purposes described.

In witness whereof I have hereunto set my

signature in the presence of two subscribing
witnesses.

HOWE E. DANTZEBECHER.
